SAFETY MECHANISM FOR FIREARMS.

1,126,201.

Specification of Letters Patent.

Patented Jan. 26, 1915.

Original application filed October 25, 1912, Serial No. 727,694. Divided and this application filed July 16, 1913. Serial No. 779,270.

To all whom it may concern:

Be it known that I, GRANT HAMMOND, a citizen of the United States, and a resident of Hartford, in the county of Hartford and State of Connecticut, have invented a new and Improved Safety Mechanism for Firearms, of which the following is a specification.

My invention relates more particularly to devices for preventing the accidental and unintentional discharge of firearms, more especially of the automatic type, and an object of my invention, among others, is to provide a device of this class, simple in construction and that shall effectually perform the operations required of it.

One form of mechanism embodying my invention and in the construction and use of which the objects herein set out, as well as others, may be attained, is illustrated in the accompanying drawings, in which—

Figure 1 is a view in side elevation of a pistol embodying my invention, with parts broken out as denoted by dotted line 1—1 of Fig. 2. Fig. 2 is a front view, with parts broken out as denoted by dotted line 2—2 of Fig. 1 to show construction, a part also being broken out back of said line to show the upper end of the safety bar. Fig. 3 is a side view of a portion of my improved pistol with parts broken away to show construction.

In the accompanying drawings the numeral 5 denotes the handle, 6 the trigger guard, 7 the trigger, and 8 the barrel of a pistol embodying my invention. The back edge piece 9 of the handle has a hammer recess 10 opening out of the magazine chamber 11 within which the magazine 12 is located, this hammer recess opening through to the back edge of the handle. A hammer 13 is pivotally mounted in this recess in the usual manner and is operated by a hammer spring 14 in a well known way.

A sear 15 is pivotally mounted within the recess 10 and has a sear tail 16 projecting laterally through the wall of the hammer recess 10 into a trip recess 17

formed in the handle. The hammer is milled out on one side forming a depression 18 having a stop shoulder 19 against which a safety bar 20 rests. This safety bar is mounted beside the sear 15 and has a sliding movement longitudinally of the handle, riding on the sear and on the depressed portion of the hammer, so that it may be engaged with the stop shoulder 19, or disengaged therefrom. The upper end of the safety bar rests in a slot in a receiver 21 constituting a part of the frame and to which the barrel is secured. A safety bar tail 22 also projects through the wall of the hammer recess into the trip recess 17. A sear spring 23 located in a hole in the back edge piece 9 forces the sear normally into engagement with the notches in the hammer, and a safety bar spring 24 forces the safety bar upward to normally engage the stop shoulder 19.

A tripping rod 25 projects through the wall of the guard 6, resting in contact with the trigger 7. Within the handle the tripping rod curves toward one side to avoid the magazine, and then passes along the side of the magazine, its end being formed into a trip 26 located in the trip recess 17. This trip has a sear shoulder 27 arranged to engage the sear tail, a safety bar cam 28 and a trip cam 29, the latter to engage the upper wall of the trip recess 17.

In the normal position of the parts it will be noted that the safety bar 20 rests against the stop shoulder 19 on the hammer, preventing it from touching the firing pin, and it will, therefore, be impossible to transmit any blow, from the hammer to the firing pin, and thus accidentally discharge the pistol. Likewise in pulling the hammer backward, should it accidentally slip from the clasp of the thumb the pistol will not be discharged, as the safety bar will prevent the force of the hammer from being transmitted to the firing pin.

In operation, the hammer being cocked in the usual manner, pressure upon the trigger 7 is transmitted through the tripping

rod 25 to the sear 15 and safety bar 20. In this movement of the tripping rod the safety bar cam 28 acts against the safety bar tail, moving the safety bar downward 5 from in front of the shoulder 19 on the hammer. At the same time the sear shoulder 27 engaging the sear tail 16 forces the sear from engagement with a notch in the hammer, the safety bar, however, being lowered from in front of the shoulder 19 before disengagement of the sear from the hammer notch. During this backward movement of the tripping rod the trip cam 29, acting against the projection formed by 15 the upper wall of the trip recess 17, moves the tripping rod downward, disengaging the sear tail 16 from the sear shoulder 27, this after the hammer has been thrown forward, so that the sear is now free to swing backward under the influence of its spring to re-engage a notch in the hammer as the latter is automatically cocked in the backward movement of the breech bolt, this action preventing "doubling." 20

25 It will be noted that the simultaneous action of the two cams 28 and 29 imparts a faster movement to the safety bar than to the tripping rod, the operation above described releasing the hammer that is forced forward by its spring in the usual manner to fire the pistol.

While I have shown and described herein a preferred form of mechanism for accomplishing the results desired by me, this may 25 be changed to a greater or lesser degree and yet be within the spirit and intent of the invention.

The invention forming the subject matter of this application was originally included 40 in my co-pending application of Ser. No. 727,694, filed October 25th, 1912.

I claim:

1. A firing mechanism for a firearm including a hammer, a safety bar to engage 45 with the hammer to prevent its forward movement, a sear in engagement with the hammer, a member movably mounted and having a cam surface engaging the safety bar to disengage it from the hammer, a shoulder engaging the sear to disengage it from the hammer, and means for disengaging said member from the sear.

2. A firing mechanism for a firearm including a hammer, a safety bar to engage 55 the hammer, a sear engaging the hammer, a member movably mounted and having a cam surface engaging said safety bar, a shoulder engaging said sear, and a cam surface engaging a projection to disengage said member from said sear.

3. A firing mechanism for a firearm including a hammer cut-away on one side providing a depression forming a shoulder, a safety bar located in said depression in position to engage said shoulder, a trigger, and

a connection between the trigger and said safety bar for operating the latter.

4. A firing mechanism for a firearm including a hammer cut-away on one side providing a depression forming a shoulder, a safety bar located in said depression to engage said shoulder to hold the hammer against movement, a sear, a trigger, and a connection between the trigger and sear and safety bar for operating the two latter members.

5. A firing mechanism for a firearm including a hammer, a safety bar, a member to actuate the safety bar, said member having a plural number of cam surfaces coöoperating to accelerate movement of the safety bar, and cam surfaces positioned to coact with those on said member.

6. A firing mechanism for a firearm including a hammer, a safety bar to engage the hammer, and a sliding member having a cam surface engaging the safety bar and a cam surface engaging a stationary cam surface, the two cam surfaces on said sliding member coacting to accelerate the movement of the safety bar.

7. A firing mechanism for a firearm including a hammer, a safety bar to engage the hammer, a trip member having a cam surface to engage said bar and a second cam surface to engage a stationary part of the frame, said cam surfaces coacting to accelerate the movement of the safety bar, and a trigger to engage said trip member.

8. A firing mechanism for a firearm including a hammer, a sear to engage the hammer, a safety bar, a longitudinally movable trip member having a cam surface to slidably engage the safety bar and a shoulder to engage said sear, and means for operating the trip member.

9. A firing mechanism for a firearm including a hammer, a sear to engage the hammer, a safety bar to engage the hammer, a tail projecting from the safety bar, a tail projecting from the sear, a trip actuating member located between said tails and having a cam surface to engage that on the safety bar, and means for operating the trip member.

10. A firing mechanism for a firearm including a hammer, a sear to engage the hammer, a safety bar, a tail projecting from the sear, a tail projecting from the safety bar, a trip member located between said tails and having a cam surface to engage the tail on the safety bar, means to engage the tail on the sear, said trip member also having a cam surface to engage a stationary part of the frame of the firearm, and means for operating the trip member, said cam surfaces coacting to accelerate the movement of the safety bar.

11. A firing mechanism for a firearm including a hammer, a pivotally mounted sear

to engage the hammer, a safety bar having a sliding movement against the side of the sear, a tail projecting from the sear, a tail projecting from the safety bar, a trip member located between said tails and having cam surfaces to engage the safety bar and a part of the frame to operate the safety bar

and sear, and means for operating the safety member.

GRANT HAMMOND.
